UNITED STATES PATENT OFFICE.

GUSTAVUS A. BAUER, OF CHICAGO, ILLINOIS.

ROTARY ENGINE.

1,036,779.

Specification of Letters Patent. Patented Aug. 27, 1912.

Application filed August 4, 1910. Serial No. 575,549.

To all whom it may concern:

Be it known that I, GUSTAVUS A. BAUER, a citizen of the United States, residing at Chicago, in the county of Cook and State of Illinois, have invented a certain new and useful Improvement in Rotary Engines, of which the following is a specification.

My invention relates to improvements in rotary engines and has for its object to provide a new and improved device of that sort.

It is illustrated in the accompanying drawings, wherein,

Figure 1 is a side elevation, Fig. 2 is a section along the line 2—2 of Fig. 1, Fig. 3, a section along the line 3—3 of Fig. 2, Fig. 4, a section showing parts in different relation.

Like parts are indicated by like letters in all the figures:

20 The drum A which is rigidly mounted upon the shaft A¹ rotates within the cylindrical casing A², has the two diametrically opposed lugs or bosses A³ upon its outside, each provided with the movable strip or leaf A⁴ held in contact with the inner wall of the casing A² by the spring A⁵. Steam to operate the drum is admitted through the passageway B to the distributing chamber B¹, thence through the valve chamber B² in which is located the rotary valve B³, through the steam port B⁴ into the chamber B⁵ behind the rotatable abutment B⁶ and thence into the space B⁷ between the drum and the wall of the casing. The abutment B⁶ is adapted to remain at all times in contact with the surface of the drum and to change in its position to correspond with the contour of that surface. The exhaust pipe C communicates with the chamber C¹ which in turn communicates with the spaces C² C³ between the surface of the drum and the wall of the casing. Both the drum A and the abutment B⁶ extend completely across the interior of the casing and are provided 40 with the centrally located sections D, D¹ such that their coefficients of expansion are different from the remainder of the body in order to prevent binding owing to changes in temperature. The shaft A¹ rotates with 45 in the journals E in the walls of the casing A² and is provided with the packing E¹ and packing glands E². The fly wheel or governor F is rigidly mounted upon the shaft A¹ and has pivotally mounted upon two diametrically opposed lugs F¹, the levers F² F³ provided each at one end with the weights

F⁴. The lever F² has pivotally mounted at the end farthest removed from the weight F⁴, the link F⁶ pivotally mounted at its other end upon the screw F⁷ which is located upon the lever F³ intermediate the weight F⁴ and the lug F¹. The link F⁸ is mounted at one end upon the screw F⁷ and engages at the other the pivot F⁹ in the link F¹⁰ which is pivotally mounted upon the lug F¹¹ upon the fly wheel F. The connecting rod G leads from the pivot F⁹ to the lever G¹ which is adjustably mounted upon the valve stem G² to operate the valve B³. The operation of the valve may be adjusted by means of the screw H in the wall of the fly wheel which controls the tension in the springs, and by means of the bolt K and nut K¹ to vary the position of the crank G¹ upon the valve stem G², thus varying the relative positions of valve and fly wheel.

It will be evident that while I have shown in my drawings an operative device, still many changes might be made both in size, shape and arrangement of parts without departing materially from the spirit of my invention. I wish, therefore, that my drawings be regarded as in a sense, diagrammatic.

The use and operation of my invention are as follows:—Steam is admitted through the steam pipe into the distributing chamber, passes thence into the valve chamber about the valve, out through the steam ports to exert pressure upon the rotatable abutment, thus forcing the abutment in close contact at its outermost point against the surface of the drum. The steam then passes on into the space formed between the drum and casing and exerting pressure upon one of the pivotally projecting lugs or bosses and the leaf carried by such lug, exerts a tangential rotating force. At some predetermined point the rotation of the fly wheel by means of the eccentric location of the connecting rod rotates the valve to close the ports, thus permitting the steam to act expansively as is usual in the reciprocating engine. This action continues until the opposed lug reaches the abutment whereupon the abutment is pushed up, rides through the lug and the same operation takes place upon that lug. The opposed lug, meanwhile has reached the discharge port and steam is discharged through said port leaving it ready for a further charge of steam when its rotation brings it beyond the movable

abutment. By this means, I am enabled to provide a rotary engine in which the steam is used expansively and in which by arrangement of valve mechanism and governor, I can cut off the steam supply at any desired point and in which I can cause the governor to reduce the speed or control it in any desired manner.

I claim:

- 10 1. The combination with a rotary engine of a governor comprising a fly-wheel, a plurality of levers pivotally mounted on opposite sides of the center, weights at one end of each of said levers, a link between them, a toggle joint connection, one end of said toggle pivotally mounted on one of said levers, the other on the fly-wheel, and a connection from said toggle to an engine valve.
- 20 2. The combination with a rotary engine of a governor comprising a fly-wheel, a plurality of levers pivotally mounted on opposite sides of the center, weights at one end of each of said levers, a link between them, springs in engagement with said weights adapted to resist their outward displacement, a toggle joint connection, one end of said toggle pivotally mounted on one of said levers, the other on the fly-wheel, and a connection from said toggle to an engine valve.
- 30 3. The combination with a rotary engine of a governor comprising a fly-wheel, a plurality of levers pivotally mounted on opposite sides of the center, weights at one end of each of said levers, a link between them, springs in engagement with said weights adapted to resist their outward displacement, a toggle joint connection, one end of said toggle pivotally mounted on one of said levers, the other on the fly-wheel, a connection from said toggle to an engine valve, and means for adjusting the tension of said springs.
- 40 4. The combination with an oscillating valve of a governor therefor, comprising a fly-wheel, levers pivotally mounted thereon at fulcrums intermediate their two ends, weights upon one end of each of said levers, a pin intermediate the fulcrum and the

weight on one end of said levers, a link pivotally mounted upon said pin and pivotally mounted upon the free end of the other lever, a link pivotally mounted upon said pin and in pivotal connection at its other end with a link pivotally mounted upon the fly-wheel, a connection between the free end of the link mounted upon the fly-wheel and the valve.

5. The combination with an oscillating valve of a governor therefor, comprising a fly-wheel, levers pivotally mounted thereon at fulcrums intermediate their two ends, weights upon one end of each of said levers, a pin intermediate the fulcrum and the weight on one end of said levers, a link pivotally mounted upon said pin and pivotally mounted upon the free end of the other lever, a link pivotally mounted upon said pin and in pivotal connection at its other end with a link pivotally mounted upon the fly-wheel, a connection between the free end of the link mounted upon the fly-wheel and the valve, and elastic means resisting the outward movement of said weights.

6. The combination with an oscillating valve of a governor therefor, comprising a fly-wheel, levers pivotally mounted thereon at fulcrums intermediate their two ends, weights upon one end of each of said levers, a pin intermediate the fulcrum and the weight on one end of said levers, a link pivotally mounted upon said pin and pivotally mounted upon the free end of the other lever, a link pivotally mounted upon said pin and in pivotal connection at its other end with a link pivotally mounted upon the fly-wheel, a connection between the free end of the link mounted upon the fly-wheel and the valve, and elastic means resisting the outward movement of said weights, said means comprising leaf springs rigidly mounted at one end upon the fly-wheel.
